REMOTE INDICATION APPARATUS

Arthur E. Dodd, Edgewood, Pa., assignor to The
Union Switch & Signal Company, Swissvale,
Pa., a corporation of Pennsylvania

Application November 20, 1937, Serial No. 175,672

3 Claims. (Cl. 246—124)

My invention relates to remote indication apparatus of the type wherein a pair of line wires are supplied with unidirectional current in one direction or the other or with alternating current from a source of alternating current.

One feature of my invention is the provision of apparatus of this character wherein normally inactive asymmetric units, such as electronic tubes, are utilized for controlling the character 10 of the current supplied to the pair of wires, and wherein the tubes are rendered active when and only when an indication is to be transmitted.

Another feature of my invention is the use of asymmetric units of the glow lamp type receiving 15 energy from said pair of wires for providing visual indications without the use of auxiliary devices, such as relays.

I shall describe one form of apparatus embodying my invention, and shall then point out the 20 novel features thereof in claims.

The accompanying drawing is a diagrammatic view showing one form of apparatus embodying my invention.

Referring to the drawing, the reference characters 1 and 2 designate the rails of a stretch of 25 railway track which are divided by insulated joints 3 into track sections 1T and 2T. Each track section is provided with the usual track circuit which includes a battery 4 and track 30 relays 1TR and 2TR, respectively. The relays 1TR and 2TR may, however, be operated or controlled in any desired manner, the track circuit control being illustrated merely as an example.

The reference character P designates a transformer having a primary winding 5 and three secondary windings 6, 7, and 8. The primary winding 5 is constantly supplied with alternating current from a source which is not shown in the drawing. Secondary winding 7 is connected to line wires 9 and 10 by two normally inactive asymmetric units, here shown as electronic tubes 1TZ and 2TZ. Tubes 1TZ and 2TZ are poled in opposite directions, as indicated by the arrows, and are connected in multiple with each other. Filament 11 of tube 1TZ receives energy from secondary winding 6 through an easily traced circuit including back contact 12 of track relay 1TR, and filament 13 of tube 2TZ receives energy from secondary winding 8 through another easily traced circuit including back contact 14 of track relay 2TR.

The two line wires 9 and 10 connect the apparatus thus far referred to with two asymmetric units 1TK and 2TK, here shown as glow lamps. 55 Lamps 1TK and 2TK are each connected across

the conductors 9 and 10 by a resistor 15 and are poled in opposite directions as indicated by the arrows. Resistor 15 is, of course, provided for regulating the value of the current supplied to lamps 1TK and 2TK.

I shall now assume that track section 1T becomes occupied, thereby deenergizing relay 1TR. Electronic tube 1TZ will then be rendered active because its filament 11 will be receiving energy over the previously mentioned circuit for this 10 filament. When tube 1TZ becomes active, a circuit will be established for glow lamp 1TK, which circuit may be traced over a path which passes from lower terminal of secondary winding 7 through wire 10, resistor 15, lamp 1TK, wire 9 15 and tube 1TZ, to the upper terminal of secondary winding 7.

If track section 2T instead of 1T becomes occupied, track relay 2TR will become deenergized, thereby rendering tube 2TZ active to establish 20 a circuit for glow lamp 2TK. This circuit may be traced over a path which passes from the upper terminal of secondary winding 7 through tube 2TZ, wire 9, lamp 2TK, resistor 15, and wire 10 to the lower terminal of secondary winding 7. 25

If now both track sections 1T and 2T become occupied, both track relays will become deenergized. Under this condition both tubes 1TZ and 2TZ will be rendered active so that alternating current will be supplied to wires 9 and 10 30 from secondary winding 7 to cause both glow lamps 1TK and 2TK to become lighted.

From the foregoing description of the apparatus embodying my invention, it will be seen that when track section 1T is occupied, lamp 1TK 35 will provide a visual indication of this condition, and that when 2T is occupied, glow lamp 2TK will provide a visual indication of this condition. It, of course, follows that when both sections are occupied, the lighting of both lamps will indicate this condition. 40

Although I have herein shown and described only one form of apparatus embodying my invention, it is understood that various changes and modifications may be made therein within 45 the scope of the appended claims without departing from the spirit and scope of my invention.

Having thus described my invention, what I claim is:

1. In combination, a pair of conductors, a pair of lamps each having one of its terminals connected to one of said conductors and having its other terminal connected to the other of said conductors whereby said lamps are illuminated 55

by current supplied over said conductors, each of said lamps being of a type which is illuminated only when supplied with current of one relative polarity, said lamps being connected to said conductors in such a manner that one of said lamps is illuminated when the conductors are supplied with current of one relative polarity and so that the other of the lamps is illuminated when the conductors are supplied with current of the other relative polarity, means for supplying current of one relative polarity to said conductors, and means for supplying current of the other relative polarity to said conductors.

2. In combination, a pair of conductors, a pair of lamps each having one of its terminals connected to one of said conductors and having its other terminal connected to the other of said conductors whereby said lamps are illuminated by current supplied over said conductors, each of said lamps being of a type which is illuminated only when supplied with current of one relative polarity, said lamps being connected to said conductors in such a manner that one of said lamps is illuminated when the conductors are supplied with current of one relative polarity and so that the other of the lamps is illuminated when the conductors are supplied with current of the other relative polarity, a source of alternating current, means for supplying current from said source of alternating current to said conductors through a circuit including an asymmetric unit adapted to permit flow of current of one relative polarity only, whereby said conductors are supplied with impulses of current of one relative polarity, and means for supplying current from said source of alternating current to said conductors through another asymmetric unit adapted to permit flow of current of the other relative polarity only, whereby said conductors are supplied with impulses of current of the other relative polarity.

mediate the impulses supplied by the other whereby when both means are effective to supply current to said conductors the conductors are alternately supplied with current of different relative polarities.

3. In combination, a pair of conductors, a pair of lamps each having one of its terminals connected to one of said conductors and having its other terminal connected to the other of said conductors whereby said lamps are illuminated by current supplied over said conductors, each of said lamps being of a type which is illuminated only when supplied with current of one relative polarity, said lamps being connected to said conductors in such a manner that one of said lamps is illuminated when the conductors are supplied with current of one relative polarity and so that the other of the lamps is illuminated when the conductors are supplied with current of the other relative polarity, a source of alternating current, means for supplying current from said source of alternating current to said conductors through a circuit including an asymmetric unit adapted to permit flow of current of one relative polarity only, whereby said conductors are supplied with impulses of current of one relative polarity, and means for supplying current from said source of alternating current to said conductors through another asymmetric unit adapted to permit flow of current of the other relative polarity only, whereby said conductors are supplied with impulses of current of the other relative polarity.

ARTHUR E. DODD.
